UNITED STATES PATENT OFFICE.

HEYMAN ROSENBERG, OF NEW YORK, N. Y.

METALLIC FASTENER.

Original application filed June 26, 1922, Serial No. 570,912. Divided and this application filed December 22, 1923. Serial No. 682,268.

This invention relates to improvements in metallic fasteners, and more particularly to the pin type adapted to be driven to the securing position, such, for instance, as is shown in my co-pending application for United States Letters Patent Serial No. 570,912, filed June 26, 1922, and of which this is a division.

Among the objects in view is the efficient anchorage of parts by a pin-like structure with the greatest possible facility and at the least expense.

With this and further objects in view as will in part hereinafter become apparent and in part be stated, the invention comprises certain novel constructions, combinations and arrangements of parts as subsequently specified and claimed.

In the accompanying drawings,

20 The figure is a view in side elevation of a metallic fastener embodying the features of the present invention, the parts being shown on a considerably magnified scale beyond the size of the average commercial article.

25 Referring to the drawings by numerals, 1 indicates the body of a pin preferably formed with a driving head 2 and provided with outstanding projections 3, 3, scattered about and projecting radially from the surface of the body 1. The projections 3 are preferably formed integral with the body, and are also preferably arranged in such relation to each other as to form rows arranged in lines corresponding with the lines of high-pitched threads. The projections 3 may, of course, be otherwise arranged when preferred, and it is also desirable that the lower-most projections 3 shall be spaced above the lower extremity of the body 1 for leaving 30 a pilot portion at such extremity.

40 Each projection 3 has four sloping sides meeting at an apex, and forming in complete outline the shape of a conventional diamond, the two lower inclined faces having a meeting edge forming an entering cutting edge. The upper sloping faces of each projection 3 also meet in a corresponding edge which functions principally only when an effort is made to withdraw the pin 1. The upper inclined surfaces provide an underhanging portion for cooperating with an overhanging portion of the material of the work produced by the flow of the metal as herein-after mentioned. The upper cutting edge

and the upper sloping faces of each of projections 3 render it possible to withdraw the pin 1 after the same has been introduced into metal under the required withdrawing stress. While pin 1 may thus be withdrawn, such withdrawal must be effected only under considerable stress, so that the fastener 1 is very effective for all fastening purposes.

When the fastener is to be used, it is preferable to form an opening in the material into which the fastener is to be inserted, 45 which opening corresponds in transverse contour to that of the body 1, so that the pilot end of the body may be readily inserted into the opening. As the projections 3 extend beyond the opening, the pin may be introduced into the material only by being driven until the projections 3 enter the surrounding metal, each of said projections forming a channel-like opening in the metal either by causing the flow of the metal or by cutting 50 the metal. The driving of the pin may be accomplished in any known manner, as by the delivery of blows on the head 2 by an appropriate hammer. The usual action of each projection 3 is to sever the metal and 55 then cause it to flow and during the flow of the metal a certain portion of it will flow back into the channel or groove cut by each projection 3 in position to overhang the projection 3. This overhanging portion cooperates to afford an effective resistance to 60 the withdrawal of the pin.

65 Each projection 3 is hardened to an extent sufficient for entering or cutting metal, such as soft iron or soft steel, substantially without injury to the projections. The projections may be hardened by any well known process, such, for instance, as by case-hardening the entire fastener by the usual cyanide process.

70 What is claimed is:—

75 1. A metallic fastener comprising a pin-like body and a projection of substantially diamond shape in marginal outline, said projection outstanding from the body and 80 being arranged with one of the acute angles of the diamond positioned generally in the direction of advance of the body when being driven into work.

85 2. A metallic fastener comprising a pin-like body and a series of projections each substantially diamond shape in marginal outline, said projections outstanding from

the body and being arranged in a substantially spiral alinement thereon.

3. A metallic fastener comprising a pin-like body and a projection of substantially 5 diamond shape in marginal outline, said projection being of solid mass integral with the body and outstanding therefrom and having

four plane sides sloping both longitudinally and laterally from a substantially central point to and blending into the body.

In testimony whereof I affix my signature.

HEYMAN ROSENBERG.
